(57) **CLAIM**

The ornamental design for a product display and vending cart, as shown and described.

DESCRIPTION

FIG. 1 is a perspective view of the product display and vending cart.

FIG. 2 is a top view of the cart shown in FIG. 1.

FIG. 3 is an end view of the cart shown in FIG. 1.

FIG. 4 is a view of the end of the cart opposite that shown in FIG. 3; and,

FIG. 5 is a side view of the cart shown in FIG. 1, the opposite side being a mirror image thereof.

The broken line disclosure shown in the drawing is for illustrative purposes only and forms no part of the claimed design.
